ONE TUBE RADIOPHONE

Winfield R. Koch, Camden, N. J., assignor to
 Radio Corporation of America, a corporation of
 Delaware

Application January 27, 1934, Serial No. 708,539

8 Claims. (Cl. 250—20)

My invention relates to radio receivers and particularly to improvements in receivers of the type which is suitable for use in an airplane or other vehicle. For such use it is essential that limitations be imposed upon the weight and bulk of the receiver.

Where weight and portability are of no consequence, sensitivity, selectivity, volume of sound reproduction and other desirable features may 10 easily be had in a radio receiver by adding the necessary tubes and stages of amplification and by providing a sufficiently high powered source of energy; but where space and weight become important considerations, numerous difficulties are 15 encountered in designing such a receiver as would be suitable for receiving beacon signals, weather reports and other communications required by aviators.

Accordingly, my invention has for its object 20 to provide a radio receiver which is small, light, simple and rugged in construction.

A further object of my invention is to provide a radio receiver which requires only one tube and which, therefore, can be operated from the lighting 25 circuit of an airplane, if desired, or from a few dry cells or other source of power which would be of minimum weight.

Another object of my invention is to provide a radio receiver of the type indicated above in 30 which a single electron tube may be utilized to obtain a high degree of gain in the amplification of signals.

The novel features that I consider characteristic of my invention are set forth with particularity in the appended claims. The invention itself, however, both as to its organization and its method of operation together with additional objects and advantages thereof will best be understood from the following description of a specific 35 embodiment when read in connection with the accompanying drawing in which the single figure thereof is a circuit diagram showing the essential features of my one-tube receiver.

Referring now to the drawing, I show an electron tube 1 which is preferably of the combined pentode-triode type. Such a tube is at present 40 available on the market and is known as an RCA 6F7 tube. The tube is characterized as having a pentode portion comprising a heating element 2, a cathode 3, an anode 7 and three grids, one of which is a control grid 4, the second a screen grid 5 and the third a suppressor grid 6 connecting with the cathode 3.

The aforementioned cathode 3 and heating element 2 are common to both the pentode and

triode portions of this tube. The triode portion also comprises its own anode 9 and control grid 8.

My receiving circuit is adapted to respond to space signals as collected by any suitable antenna 21. A response to the signals may be had through the radio frequency transformer 22 and the tuned circuit which includes the tuning condenser 23. The signals are then transferred through the blocking condenser 24 to the control grid 4. The radio frequency signals are first amplified through 10 the action of the pentode portion of the tube 1, the output circuit of which includes the primary winding of a radio frequency transformer 12. The secondary winding of this transformer is tunable by means of a variable condenser 14. A common 15 control may be provided for the two tuning condensers 23 and 14.

The radio frequency signals are then transferred through the blocking condenser 11 to the control grid 8 in the triode portion of the tube. 20

This control grid is provided with a grid leak 10 whereby the triode portion of the tube acts as a detector. The output circuit connecting with the anode 9 includes a regenerative coil 13 which is coupled with the transformer 12. Energy is 25 supplied by the battery or other source 32 for impressing suitable potentials upon the various electrodes, both of the pentode portion and of the triode portion of the tube.

As shown in the diagram, the screen grid 5 may have impressed thereon the highest potential while the potential of the anode 7 may be made only slightly lower due to the comparatively low voltage drop through 30 the phones 31 and the primary of the radio frequency transformer 12.

The voltage applied to the anode 9 is made variable by including in the output circuit thereof a potentiometer 15 having a movable tap 16 associated therewith. This tap is connected to the primary 26 of an audio frequency transformer 25. As shown in the diagram, 40

when the tap is moved to the right the portion of the potentiometer 15 which is shunted by the primary winding 26 becomes diminished. Since the primary winding 26 has a comparatively low 45 ohmic resistance, it will be seen that the voltage impressed upon the anode 9 through the regenerative coil 13 may be increased by moving the tap 16 to the left (as shown in the diagram) whereby

more of the resistance in the potentiometer 15 is bypassed. Furthermore, the radio frequency currents through the regenerative coil 13 may be 50 more or less impeded by adjusting the setting of the tap 16, since these currents are fed through the left hand portion of the potentiometer 15 to the tap 16 and thence through the bypass con-

denser 17 to ground. The adjustment of the potentiometer serves, therefore, to control the amount of regeneration set up by the coil 13.

The potentiometer has, however, a dual purpose. Its adjustment provides a secondary effect; namely, that of increasing or decreasing the portion of the signalling energy which, after rectification, may be impressed through a primary 26 of the audio frequency transformer 25 so as to step up the voltage of the audio signals and reflex the same from the secondary 27 of this transformer upon the control grid 4 of the pentode portion of the tube. This reflex circuit includes a resistor 28 which serves as a relatively low impedance to audio frequency currents but a high impedance to radio frequency currents. In place of the resistor 28 a radio frequency choke might be used, although, for economy of cost and space the resistor appears to be preferable. It will be noted at this point that the blocking condenser 24 is of such capacitance that it serves to prevent the dissipation of the reflexed audio frequency signals back to ground through the low resistance secondary of the radio frequency transformer 22.

Following out further the action of the audio frequency signals as impressed upon the control grid 4, it will be seen that they are amplified through the pentode portion of the tube, the output circuit of which leads to the phones or other sound reproducing device 31.

The remaining features of my improved and simplified one-tube receiving circuit may be well understood by those skilled in the art. For the purpose of completeness of the description, however, they are referred to as follows:

The bypass condenser 17 may be interposed between the tap 16 of the potentiometer and ground in order to afford a free path for radio frequency components in the output circuit of the regenerative detector. A similar bypass condenser 30 is provided across the terminals of the sound reproducing device 31 which would otherwise afford an undesirably high impedance to radio frequency currents in the output circuit of the pentode portion of the tube.

The resistor 29 may be used across the leads to the phones 31 so as to straighten out the response characteristic of the latter in respect to different audio frequencies.

The resistor 19 provides a difference of potential between the cathode 3 and ground in order to properly bias the pentode grid 4. It is, therefore, employed as the usual self-bias resistor in the cathode return lead 33. The fixed condenser 18 is of the order of several microfarads in order that the radio and audio frequency components of the plate currents through each portion of the tube may be bypassed to ground without transferring any voltages to the other portion of the tube.

It will be seen from the above and will also be recognized by those skilled in the art that the circuit as herein described has many advantages. The single tube itself is of a rugged type capable of withstanding the vibrations and shocks incident to the carrying of a radio receiver in an airplane or automobile. This tube also has its advantages for use in a receiver of this type in that it is not necessary to provide more than 45 to 67 volts of plate potential, and the current drain is such that very small B-battery blocks might be used. In view of the now accepted practice of obtaining plate voltages by a vibrator and filter system acting in conjunction with

a low voltage battery, it will be seen that one of the principal objects of my invention is achieved in that it is suitable for operation by a power plant of minimum weight. Furthermore, simplification is achieved by the provision of a potentiometer which is so constituted that it serves a dual purpose; namely, to control the regeneration and also the volume of audio frequency energy transferred to the reflex circuit. 5

In an embodiment of my invention which has been built, it was found that a sensitivity of better than 250 microvolts could be obtained. 10

Although I have disclosed herein certain specific means for accomplishing the objects of my invention, these are given merely by way of example and are not to be construed as limitations to the scope of my invention. Other modifications will suggest themselves to those skilled in the art. My invention, therefore, is not to be limited except insofar as is necessitated by the prior art and by the spirit of the appended claims. 15 20

I claim as my invention:

1. In a radio receiver, a pentode-triode tube, means including the pentode-electrodes of said tube for amplifying radio-frequency signals, 25 means including a tuned circuit to which the radio frequency output from the pentode electrodes of said tube is coupled for impressing signals to be detected upon the triode electrodes of said tube, an output circuit for said triode electrodes regeneratively coupled to said tuned circuit, a potentiometer in said output circuit, an audio frequency transformer the primary of which connects between one end of said potentiometer and a variable tap intermediate thereof while the secondary of said transformer connects through a suitable radio frequency impedance with the input electrode of the pentode portion of said tube, and means including said variable tap for controlling both the amount of regeneration and the volume of the signals passed through said audio frequency transformer. 30 35 40

2. In a radio receiver, radio frequency amplification means, a radio frequency detector having a regenerative output circuit, including a potentiometer, an audio frequency transformer having its primary connected in shunt with a variable portion of said potentiometer and its secondary connected from ground through a suitable radio frequency impedance to the input side of said radio frequency amplification means, means including an audio frequency amplifier having elements thereof in common with those of the radio frequency amplification means whereby a desired gain in audio frequency signal strength may be obtained, a sound reproducing unit responsive to audio frequency signals as delivered by said audio frequency amplification means, and means including an adjusting member acting solely upon said potentiometer to vary the degree of regeneration and simultaneously to control the voltage drop across the primary of said audio frequency transformer for effecting a desired volume of signal response in said sound reproducing unit. 55 60 65 70

3. A device in accordance with claim 2 further characterized in that a pentode-triode electron tube is provided in which the electrodes of the pentode portion are included in the radio frequency amplification means and also in the audio frequency amplification means, while the electrodes of the triode portion constitute a detector. 75

4. In a radio receiver, a single electric discharge tube having input and output electrodes 75

- thereof common to the functions of amplifying both radio frequency and audio frequency signals, means including additional electrodes of said tube connected on the input side with a resonant circuit and on the output side with a regenerative coil and thence through a potentiometer to a source of direct current for detecting and amplifying said signals, an audio frequency transformer, and means including an adjustable tap on said potentiometer for bypassing audio frequency signals in varying degree around a portion of said potentiometer and through said transformer, said means serving further for simultaneously controlling both the impedance path for radio frequency currents through said regenerative coil and also the direct current potential applied to one of said additional electrodes, specifically the anode thereof.
5. In a radio receiver, a thermionic device having at least two output circuits and at least two input circuits, one input circuit for each output circuit, means for reflexing signal-representative potentials from one of said output circuits to the input circuit corresponding to the other of said output circuits and unitary means for simultaneously controlling the amplitude of the said potentials in the output circuit from which they are derived and the amplitude of the derived potentials reflexed into the input circuit.
10. In a radio receiver, an electron tube having a first set of input and output circuits and a second set of input and output circuits, radio and audio frequency amplification means constituted by the first set, regenerative signal detection means constituted by the second set, coupling
- means for reflexing signal representative potentials from the output circuit of the second set to the input circuit of the first set, and means constituted solely by an adjustable potentiometer for controlling the amplitudes of the radio frequency and audio frequency components of the potentials in the input and output circuits of the second set while simultaneously controlling the amplitude of the derived audio frequency potentials reflexed into the input circuit of the first set.
15. In a radio receiver, two stages of amplification, one stage of regenerative demodulation, coupling means for impressing modulated potentials derived from the first stage of amplification upon said stage of demodulation, coupling means for impressing demodulated signal-representative potentials upon the second stage of amplification, and means comprising an adjustable potentiometer for controlling the amount of regeneration while simultaneously controlling the amplitudes of the signal-representative potentials both in the stage of demodulation and in the second stage of amplification.
20. A device in accordance with claim 7 wherein the potentiometer is so connected between the stages that its adjustment one way results in a diminution of amplitudes both of the direct current component and of the alternating current components in the stage of demodulation, and its adjustment the other way results in an increment 25 of potential drop of the signal-representative potentials impressed upon the coupling means feeding to the second stage of amplification.
25. In a radio receiver, an electron tube having a first set of input and output circuits and a second set of input and output circuits, radio and audio frequency amplification means constituted by the first set, regenerative signal detection means constituted by the second set, coupling
30. 6. In a radio receiver, an electron tube having a first set of input and output circuits and a second set of input and output circuits, radio and audio frequency amplification means constituted by the first set, regenerative signal detection means constituted by the second set, coupling
35. 7. In a radio receiver, two stages of amplification, one stage of regenerative demodulation, coupling means for impressing modulated potentials derived from the first stage of amplification upon said stage of demodulation, coupling means for impressing demodulated signal-representative potentials upon the second stage of amplification, and means comprising an adjustable potentiometer for controlling the amount of regeneration while simultaneously controlling the amplitudes of the signal-representative potentials both in the stage of demodulation and in the second stage of amplification.
